UNITED STATES PATENT OFFICE.

GUSTAVE HYMAN, OF NEW YORK, N. Y., ASSIGNOR TO STRAUSS, SACHS & CO., OF SAME PLACE.

HARMONICA.

SPECIFICATION forming part of Letters Patent No. 505,223, dated September 19, 1893.

Application filed May 11, 1893. Serial No. 473,833. (No model.)

To all whom it may concern:

Be it known that I, GUSTAVE HYMAN, of New York city, New York, have invented an Improved Harmonica, of which the following 5 is a specification.

This invention relates to a harmonica provided with a slide or lid over the mouth piece, so that the interior of the harmonica may be protected against dust and moisture when 10 not actually in use.

In the accompanying drawings: Figure 1 is a perspective view of my improved harmonica; Fig. 2 a side elevation of the same; Fig. 3 an enlarged cross section of a modification; Fig. 4 a top view of a further modification; Fig. 5 an enlarged cross section of a further modification; Fig. 6 an elevation of Fig. 5.

My improved harmonica is provided with 20 the usual reed plates and mouth piece and may be of suitable size and ornamentation.

To the right and left of the mouth piece *a*, I form upon the reed plates *b*, or otherwise, grooves or rails *a'*, which are engaged by the 25 flanged ends *c'*, of a sliding lid or cover *c*. When this cover is projected over the mouth piece, the latter is entirely concealed and the wind openings are closed, so that neither dust nor moisture can enter the body of the harmonica.

In Figs. 1 and 2 the slide *c*, is shown to be made solid, while in Fig. 4 I have shown it provided with perforations *c*², arranged to correspond substantially with the wind openings in the mouth piece. If the slide is fully closed, the solid parts of the slide will cover and protect the wind openings, but when the slide is partly withdrawn and the openings in the parts *a*, and *c*, made to register, the 35 instrument may be played upon. Thus in 40

this modification, it is not necessary to detach the slide from the harmonica when the latter is to be used.

In Fig. 3 the grooves or rails are not formed on the reed plates *b*, but on covering plates 45 *d*, as shown at *d'*. These covering plates are themselves separately removable, being interlocked at their upper ends with the lid *c*, as described and entering with their flanged lower ends *d*², longitudinal grooves *e'*, in the 50 base plate or body *e*, of the instrument.

In Figs. 5 and 6 the construction is the same as in Fig. 3, excepting that I employ in addition to the two sliding covering plates *d*, and sliding lid *c*, a sliding back *f*, which is 55 joined to the plates *d*, in the same manner as the lid. With this construction, any one side or end of the harmonica *a* may be separately uncovered for inspection and repair.

What I claim is—

1. A harmonica provided with a removable lid adapted to be projected over the perforated mouth piece, substantially as specified.

2. The combination of a harmonica having grooves at the sides of the mouth piece, with 65 a flanged sliding lid engaging such grooves, substantially as specified.

3. The combination in a harmonica of a sliding lid over the mouth piece with sliding covering plates over the reed plates that engage the sliding lid, substantially as specified. 70

4. The combination in a harmonica of a sliding lid and back with sliding covering plates engaging the lid and back, substantially as specified.

GUSTAVE HYMAN.
